UNITED STATES PATENT OFFICE.

JOHN KATULKA, OF NANTICOKE, PENNSYLVANIA.

COAL-DRILL.

No. 844,872.

Specification of Letters Patent.

Patented Feb. 19, 1907.

Application filed November 30, 1906. Serial No. 345,708.

To all whom it may concern:

Be it known that I, JOHN KATULKA, a citizen of the United States, residing at Nanticoke, Luzerne county, State of Pennsylvania, have invented certain new and useful Improvements in Coal-Drills, of which the following is a specification.

The present invention relates to improvements in coal drills or augers, and has for its object to provide a drill which shall be more durable and effective in operation than the devices heretofore commonly employed.

In the accompanying drawings, Figure 1 is an elevation of a coal-mining drill constructed in accordance with the present invention. Fig. 2 is a view of the cutting-head detached from the stem or body of the drill and viewed in a direction substantially at right angles to the side exposed in Fig. 1. Fig. 3 illustrates the form of bore made by the improved drill.

Referring to the drawings, the stem or body of the drill 1 is provided with ribs or flanges, which form a spiral way or passage extending longitudinally of the stem, by means of which the cuttings produced by the cutting-head, hereinafter described, will be removed from the bore produced by rotating the drill, and thus prevent clogging or obstruction of the cutting edges.

At one end the stem 1 is provided with a suitable socket, preferably polygonal in cross-section, adapted to receive a correspondingly-shaped stud or pin on the cutting-head. The latter comprises a central or main cutter 2, made in the form of an auger and having its free end split to provide two oppositely curved cutting-points 3 4 and a pair of auxiliary or supplemental cutters 5 6, which are arranged on opposite sides of and extend longitudinally of the central cutter 2. Said parts 2 5 6 are formed integral and preferably of soft steel. The auxiliary cutters 5 6 are of different lengths, and the point or free end of the cutter 5 is relatively closer to the central auger-like cutter 2 than the other shorter auxiliary cutter 6. The inner edge of the auxiliary cutter 5 is in substantially the same longitudinal plane as the outer end of the cutting-point 3, and the inner edge of the cutter 6 is substantially at the same distance from the axis of the central auger-like cutter 2 as the outer edge of the other auxiliary cutter 5.

The polygonal shank or stud 7 on the cutting-head is of such size and form as to fit

closely in the socket in the stem 1 and may be held therein by a key 9, extending through a notch 8, formed in said shank.

It will be seen that the central auger-like cutter projects some distance beyond the points of the auxiliary cutters 5 6, which, as above noted, are of different lengths, and therefore in operation said central cutter will form a relatively small pocket 10, while the auxiliary cutters 5 6 will respectively form cuttings 11 12, the latter being of substantially the same diameter as the stem 1. By this construction the central cutter 2 acts to securely support and guide the auxiliary cutters 5 6, which rapidly enlarge the passage formed by the cutting-points 3 4 to the full diameter of the drill.

By forming all of the cutters from a single piece and employing soft steel it is possible to provide a very durable bit, and by arranging the respective cutters in the manner illustrated and described the drill may be operated by a minimum amount of power.

Having thus described the invention, what is claimed, and desired to be secured by Letters Patent, is—

1. The herein-described coal-drill comprising a stem provided with ribs forming a spiral way or passage about the stem, a centrally-arranged auger-like cutter at one end of said stem, and two auxiliary cutters of different lengths, formed integral with and arranged on opposite sides of said main cutter, the longer auxiliary cutter having its cutting edge closer to the main cutter than the other, shorter, auxiliary cutter, substantially as and for the purpose described.

2. The herein-described coal-drill comprising a spirally-grooved stem, and a cutting-head detachably connected with said stem and including a central auger-like cutter, terminating in two oppositely curved cutting-points, and two auxiliary cutters extending longitudinally of and arranged on opposite sides of said central cutter, said auxiliary cutters being curved longitudinally and of different lengths, and the longer one being arranged closer to the central cutter than the other, shorter, one.

In testimony whereof I affix my signature in presence of two witnesses.

JOHN KATULKA.
